PHOTO ELECTRIC CELL

Filed Oct. 18, 1928

FIG. I.

FIG. 2.

FIG. 3.

Inventor
SAMUEL RUBEN

By his Attorney M. McClellan

UNITED STATES PATENT OFFICE.

SAMUEL RUBEN, OF NEW YORK, N. Y.

PHOTO-ELECTRIC CELL.

Continuation of application Serial No. 238,217, filed December 6, 1927. This application filed October 18, 1928. Serial No. 313,369.

This invention relates to a photo-electric cell. The object of the invention is the provision of cells of this type of high sensitivity.

This application constitutes a continuation 5 of my copending application bearing Serial Number 238,217.

In my said prior application I described a photo-electric cell in which the electron emission from the cathode is controlled by 10 photo-electric response to resistance changes of the photo-sensitive control element, the surface of which is composed of fused cuprous oxide. The oxide is produced by heating a copper base in an oxidizing atmosphere and 15 quenching it in hydrochloric acid to produce the desired crystalline structure and also to reduce the surface layer of cupric oxide, after which quenching any undesirable by-products of the reaction between the hydrochloric 20 acid and the cuprous oxide is removed by mechanical or chemical means, such as immersion in a diluted nitric acid solution to assure a thoroughly cleansed surface.

I have found that other compounds are likewise photo-sensitive. I refer particularly to the compounds of the oxygen series in the sixth periodic group. These photosensitive materials are such as molybdenum sulphide, 25 silver sulphide, and silver selenides. I have also found that mixtures of oxides and sulphides, or oxides and selenides, or tellurides, can be made photo-electrically responsive. In 30 all these materials it is important that the proper crystalline structure be obtained.

This may be done by the method described in my said prior application, as by heating and causing a reaction between the metal and a vapor of one of the elements named to produce 35 a surface of a photosensitive compound.

Where a higher resistance is desired, instead 40 of quenching, a very slow cooling can be employed which permits the formation of large crystals. For some applications the long crystal has advantages over the short one.

To produce silver sulphide, a silver body of 45 a proper form is heated in a sulphur atmosphere and then heat treated to obtain the most efficient crystalline structure. Molybdenum is likewise treated. To produce selenides, a 50 selenium vapor is used with the proper base material; it is likewise with respect to tellurides. Where mixtures are desired they can

be applied in the form of a coating of finely ground crystals with a suitable binder which is volatilized so as to leave a residue 55 that will not cause too great a pressure effect in the evacuated tube. Particularly I have noted that the photosensitivity of conductive crystalline compounds produced by a reaction with an element of the oxygen series 60 compounds decreases with decreased electro-negative characteristics or with the higher atomic numbers.

My invention then, consists of a photo-electric cell having three electrodes, a cathode, 65 anode and grid, the last of which comprises a metal body having integrally formed on its surface a photo-sensitive compound of the oxygen series in the sixth periodic group. In this device, the grid is operated through the 70 intermittent exposure of the surface of the photo-sensitive compound to light rays, thereby varying its electrical resistance and correspondingly, its potential employed to vary the distribution of the electron stream over 75 the plate surface and therefore the current flow in the cathode-anode circuit. The control electrode or grid may be composed of copper or any other suitably conductive metal base, having a suitably exposed surface of an 80 integrally formed homogeneous, non-porous, photo-sensitive compound of the oxygen series in the sixth periodic group.

Reference is made to the accompanying drawings of an embodiment of this invention 85 in which, in Figs. 1, 2, and 3, the control elements are surfaced respectively with cuprous oxide, silver sulphide and silver selenide, the other elements in the tube being, 1, a filamentary cathode coated with an alkaline 90 earth oxide and supported by leads 1_a and 1_b, and anode 2, mounted on lead 2_a. The photo-sensitive control element in the tube extends upon two sides of and parallel with the anode.

With the tube in operation, the cathode-anode current discharge is varied in response to changes in the external light rays impinging upon the photo-sensitive grid coating.

What I claim is:

1. In a photo-electric cell, a control element 100 comprising a copper body having integrally formed on its surface a photo-sensitive compound of said body.
2. In a photo-electric cell, the combination

of a cathode, an anode and a control electrode composed of a copper body having a surface of an integrally formed, homogeneous, non-porous crystalline compound of said copper body.

3. In a photo-electric cell, a control element comprising a metal body having an exposed surface of a photo-sensitive copper compound.

4. In a photo-electric cell a control element comprising a metal body having formed on its surface a photo-sensitive compound of the oxygen series of the sixth periodic group.

In testimony whereof, SAMUEL RUBEN has signed his name to this specification this 16th day of October 1928.

SAMUEL RUBEN.
